UNITED STATES PATENT OFFICE.

OSCAR HEEREN, OF BIARRITZ, FRANCE.

GOLF-CLUB.

SPECIFICATION forming part of Letters Patent No. 734,065, dated July 21, 1903.

Application filed January 24, 1903. Serial No. 140,426. (No model.)

To all whom it may concern:

Be it known that I, OSCAR HEEREN, gentleman, a subject of the King of Spain, residing at Villa Heeren, Biarritz, France, have invented certain new and useful Improvements in Golf-Clubs, of which the following is a specification.

The object of this invention is to obtain a striking-face which is not only hard, but is also in the highest degree elastic. For this purpose I employ "glass," under which term I include substances having the same properties as glass, such as quartz, crystals, flint, and the like; but it does not include any comparatively inelastic substance, such as earthenware. The glass is generally in the form of a block let into and secured in the head of a club.

Figure 1 is a front elevation of a club made

according to this invention; and Fig. 2 is a section on the line 2 2, Fig. 1.

a is a block of glass let into the wooden head *b* and secured by pins *c*, which lie in grooves in it and pass through the ordinary horn sole-plate *d* into the head *b*. *e* is lead for weighting the club.

I claim—

1. A golf-club having a striking-face of glass.
2. In a golf-club, the combination of a head having a hollow in its face, a block of glass fitting into the hollow, and pins engaging with grooves in the block and entering holes in the head.

OSCAR HEEREN.
